UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

AIR AND WATER TUBE.

Application filed January 3, 1924. Serial No. 684,151.

This invention relates to fluid actuated percussive machines, but more particularly to rock drills of the hammer type which employ concentrically arranged liquid conveying and gaseous fluid conveying tubes for introducing a mixture of liquid and gaseous fluid, such as water and air, into the drill steel for cleansing the drill hole.

In order to cleanse the drill hole, most rock drills of the hammer type employ a tube which extends through the machine and communicates with the hollow drill steel for conveying liquid under pressure, usually water, for washing the cuttings from the drill hole. In order that there may be sufficient pressure upon this water, some of the pressure fluid which is employed for actuating the hammer piston, is usually permitted to escape into the drill steel and mix with the water and thereby create a greater pressure to remove the cuttings. Under some circumstances, however, there is insufficient pressure fluid escaping past the hammer piston to remove the cuttings and two concentrically arranged tubes have been used, one of which is adapted to convey gaseous fluid and the other a liquid. In this manner the amount of pressure fluid introduced into the drill steel may be materially increased, so that the removal of the cuttings from the drill hole may be efficiently effected.

One object of this invention is to enable concentrically arranged gaseous fluid and liquid conveying tubes to be securely held in place in a rock drill of the hammer type by an improved and simplified means.

Further objects of the invention will hereinafter appear and the invention is shown in one of its preferred forms in the accompanying drawings, in which

Figure 1 is a side elevational view partly in vertical section of a stope drill, and

Figure 2 is an enlarged detail fragmentary view showing the manner in which the liquid conveying and gaseous fluid conveying tubes are held in place in a stope drill.

Referring to the drawings, the invention is shown embodied in a stope drill in which the cylinder A is separated from the front head B by the usual front cylinder bushing C in which is located in this instance, an anvil block D. The usual side bolts (not shown) connect the front head B to the cylinder A, and a hollow drill steel E is

adapted to extend into the front head B for receiving the impact blows of the hammer piston F through the medium of the anvil block D. In this instance the hammer piston F serves as the percussive element and controls the distribution of motive fluid for actuating the piston, although a suitable distributing valve may be employed, if desired. The supply of motive fluid to the hammer piston is controlled by a suitable throttle valve G preferably located in the back head J and having a handle H to enable the valve to be readily manipulated. The back head J in this instance forms a closure for the cylinder A although the back head and cylinder could conceivably be formed in one piece. A rotation handle K is preferably connected to the back head J for manually rotating the machine in order to keep the drill steel E free in the drill hole, to obtain efficient drilling.

The fluid pressure feeding element L preferably comprises a cylinder O, which is in this instance separated from the back head J by a head block P, and a piston in the cylinder having a piston rod Q, which is preferably provided with a rock engaging pointer R. It will be understood that this invention may be applied to rock drills of the drifter type and in this event the fluid pressure feeding element is dispensed with. The feed cylinder O, head block P and back head J are in this instance connected together by the usual bolts S and nuts T. As the above arrangement of elements forms no part of the present invention, and is shown on the drawings for illustrative purposes only, further description is deemed unnecessary.

In accordance with the present invention, concentrically arranged tubes U and V are preferably held respectively in the back head J and head block P. The tube V, which is preferably arranged within the tube U is slightly longer than the tube U, and is formed in this instance with a tapered end portion W, which is adapted to extend a short distance into the drill steel E. The tube V in this instance serves to convey liquid, such as water, into the hollow drill steel E for cleansing the drill hole of the cuttings and allaying the dust. The tube U, which is preferably slightly shorter and of greater cross sectional area than the

tube V, extends in this instance into the anvil block D and a gaseous fluid, such as air, is adapted to be introduced into the tube U. In this manner, a mixture of air and water is adapted to take place in the drill steel and the air creates additional pressure on the water for effectively cleansing the drill hole.

In order to hold the tube U in the back head J a collar X is preferably formed on the tube U adjacent one end thereof and a gland nut Y is adapted to be screwed into the back head J against the collar X and thereby prevents movement of the tube U. The tube V is preferably formed with a collar Z adjacent one end thereof, and a resilient packing a which may be of rubber, is in this instance adapted to surround one end of the tube V, and the collar Z. A sleeve b preferably surrounds the resilient packing a and a clamping washer c surrounds the tube V and in this instance bears against the collar Z. A gland nut d is screwed into the head block P about the sleeve b and in the opposite direction from the nut Y and is adapted to force the clamping washer c against the collar Z in order to compress the resilient packing a tightly about the tube V and thereby firmly hold the tube in place, so that a fluid tight connection between the end of the tube V and the head block P may be effected. Liquid is in this instance introduced into the tube V through the passages e and f in the head block P from a suitable connection g.

In order to enable the gland nuts Y and d to be counter-sunk in the back head J, and head block P respectively, the back head J is in this instance formed with a recess s, and the head block P is formed with a recess t. A ring v is preferably inserted in the recesses s and t and enables the back head J and head block P to be centered with respect to each other.

The throttle valve G is preferably formed with radial ports h and j and the port h is adapted to communicate with the passage k formed in the back head J, for supplying pressure fluid to the cylinder A for actuating the hammer piston F. Pressure fluid is in this instance supplied to the throttle valve G through a connection r, and the port j is in this instance adapted to be brought into communication with a passage o in the back head J in order to supply pressure fluid to the tube U. The port j is preferably formed wide enough to admit pressure fluid to a passage p' in the back head J which communicates with a passage p in the head block P for supplying pressure fluid to the feed cylinder O for actuating the feeding element about the same time pressure fluid is supplied to the tube U. The ports h and j in the valve G are

so arranged that the valve may first be actuated to admit pressure fluid to the feeding element before pressure fluid is admitted to the tube U and percussive element. Further movement of the valve will enable pressure fluid to pass to both the percussive element and tube U. Pressure fluid may be shut off from the tube U and percussive element yet be supplied to the feeding element in order to keep the machine in operative position relative to the drill hole. It is preferable that pressure fluid be supplied to the tube U slightly before it is admitted to the percussive element in order to keep the drill hole free from the cuttings.

I claim:

1. In a fluid actuated rock drill, the combination of a percussive cylinder, a back head for the percussive cylinder, a head block forming a closure for the back head, concentric cylindrical recesses in said head block and back head cooperating to form a cylindrical pocket when the said parts are assembled, concentrically arranged collared air and water conducting tubes, a screw threaded gland nut located in the recess in the back head for securing the air tube within the back head, means including a screw threaded gland nut and resilient packing located in the recess in the back head for securing the water tube within the head block, a sleeve within the pocket formed by the said recesses to center the back head and head block, and a throttle valve for controlling the admission of pressure fluid to the percussive cylinder and to the air tube.

2. In a fluid actuated rock drill, the combination of a percussive cylinder, a back head for the percussive cylinder, said back head having passages for conducting pressure fluid, a head block forming a closure for the back head, concentric cylindrical recesses in said head block and back head cooperating to form a cylindrical pocket when the said parts are assembled, concentrically collared air and water tubes for conducting cleansing liquid through the percussive cylinder, a gland nut located within the recess in the back head to secure the air tube within the back head, a gland nut and a packing located within the recess in the head block to secure the water tube within the head block, a throttle valve having passages adapted to register with the back head passages for admitting pressure fluid simultaneously to the percussive cylinder and to the air tube, and means for supplying water to the water tube.

3. In a fluid actuated rock drill, the combination of a percussive cylinder, a back head for the percussive cylinder, said back head having passages for conducting pressure fluid, a head block forming a closure for the back head, concentric cylindrical recesses in said head block and back head co-

operating to form a cylindrical pocket when the said parts are assembled, concentrically collared air and water tubes for conducting cleansing liquid through the percussive cylinder, a screw threaded gland in the back head recess to hold the air tube within the back head and form a fluid tight joint between said tube and back head, a threaded gland nut and a packing in the head block recess for securing the water tube adjustably within the head block, a means for centering the back head and head block, located in the pocket formed by the recesses in the back head and head block, and a throttle valve to control the admission of pressure fluid to the cylinder said throttle valve having passages adapted to register with the back head passages for admitting pressure fluid simultaneously to the percussive cylinder and to the air tube, and means for supplying water to the water tube.
